UNITED STATES PATENT OFFICE.

CHRISTIE M. NUMAN, OF CANTON, OHIO.

DESIGN FOR A CURTAIN-TACK.

SPECIFICATION forming part of Design No. 26,260, dated November 10, 1896.

Application filed August 14, 1896. Serial No. 602,815. Term of patent 7 years.

To all whom it may concern:

Be it known that I, CHRISTIE M. NUMAN, a citizen of the United States, and a resident of Canton, county of Stark, State of Ohio, 5 have invented a new and useful Design for Curtain-Tacks, of which the following is a full, clear, and exact description, reference being had to the accompanying drawings, making part of this specification.

10 My invention relates to a new design for curtain-tacks.

The design consists of a curtain-tack of the configuration shown in the accompanying drawings, in which—

15 Figure 1 is a side elevation, and Fig. 2 a plan.

In the drawings, A represents the head, circular in form, having depending from the under side and central thereto a drive-tack B,

20 and from the upper side and adjacent the edge is an upwardly-projected needle-like portion C, the upper end portion of which is turned out to one side over the edge of the head.

25 The essential features of the design consist of the flat circular head A, the central tack B, and the upwardly-projected needle C, having the point turned out over the edge of the head.

What I claim is—

30 The design for a curtain-tack as herein shown and described.

In testimony whereof I have hereunto set my hand this 28th day of July, A. D. 1896,

CHRISTIE M. NUMAN.
